ATTORNEY

UNITED STATES PATENT OFFICE.

ROBERT GAIR, OF NEW YORK, N Y.

DESIGN FOR A DOILY.

SPECIFICATION forming part of Design No. 33,809, dated December 25, 1900.

Application filed November 27, 1900. Serial No. 37,929. Term of patent 31 years.

To all whom it may concern:

Be it known that I, ROBERT GAIR, a citizen of the United States, residing at New York, borough of Brooklyn, in the county of Kings 5 and State of New York, have invented and produced a new and original Design for a Doily; and I do hereby declare the following to be a full, clear, and exact description of the invention, such as will enable others skilled 10 in the art to which it appertains to make and use the same.

In the accompanying drawings, Figure 1 represents a plan view of a doily, showing my new design. Fig. 2 is a sectional view taken 15 on line X X of Fig. 1.

As illustrated in the drawings, the leading or material feature of my design consists of a number of sprays of conventionalized flowers and leaves A A A A, disposed or arranged 20 in or near the corners of a field B, and smaller sprays C C C C, disposed on the same field between those in the corners, and in the center of the field is a conventionalized or heraldic

lion D. The field is defined by lines of perforations E E E E, which are equally distant 25 from the edges of the doily and intersect and cross each other at right angles at the corners and extend to the edges of the doily. The flowers and leaves are convex when seen in cross-section, as shown in Fig. 2. With the 30 exception of the sprays of flowers and leaves and the heraldic lion the whole of the field is plain, as are also the borders F outside of the lines of perforation.

Having described my invention, what I 35 claim as new, and desire to secure by Letters Patent, is—

The design for a doily or similar article, as herein shown and described.

In testimony that I claim the invention 40 above set forth I do affix my signature in presence of two witnesses.

ROBERT GAIR.
